UNITED STATES PATENT OFFICE.

THOMAS J. BARBOUR, OF SAN FRANCISCO, CALIFORNIA, ASSIGNOR TO THE RISDON IRON & LOCOMOTIVE WORKS, OF SAN FRANCISCO, CALIFORNIA, A CORPORATION OF CALIFORNIA.

WATER-TUBE BOILER.

SPECIFICATION forming part of Letters Patent No. 766,583, dated August 2, 1904.

Application filed March 11, 1903. Serial No. 147,235. (No model.)

To all whom it may concern:

Be it known that I, THOMAS J. BARBOUR, a citizen of the United States, residing at the city and county of San Francisco, State of California, have invented certain new and useful Improvements in Water-Tube Boilers; and I do hereby declare the following to be a full, clear, and exact description of the same.

The present invention relates more particularly to that class of tubular boilers used for marine purposes, although as well adapted for stationary work, the object of the invention being to procure a free and unimpeded circulation of the water through the water-tubes to the steam-drum, to dispense with sectional water-heads commonly used for this class of boilers, to dispense with unions or end couplings for the water-tubes, to provide a water-jacketed tubular fire-box, to increase the efficiency of this type of boilers, and to prolong the life of the boiler by reducing to a minimum liability of the tubes becoming scale-clogged.

To comprehend the invention, reference must be had to the accompanying sheet of drawings, wherein—

Figure 1 is a front view in elevation of a furnace, partly broken away, with the improved tubular boiler applied thereto. Fig. 2 is a longitudinal sectional view, in side elevation, taken on line *x-x*, Fig. 1 of the drawings. Fig. 3 is a horizontal sectional plan view, partly broken away, taken on line *y-y*, Fig. 2 of the drawings. Fig. 4 is a vertical sectional view taken on line *v-v*, Fig. 2 of the drawings; and Fig. 5 is a similar view taken on line *w-w*, Fig. 2 of the drawings.

In the drawings, the numeral 1 is used to indicate the furnace, within which the water-tube boiler is arranged. The boiler comprises a series of water-circulating boiler-tubes 2, which tubes connect, respectively, with the interior of the water-heads 3, 4. These heads are non-sectional and free of interior partition-plates, although the walls thereof are united by stay-bolts 5. As thus connected, a free circulation of the water through the tubes 2 is obtained. The rear water-head 4 prefer-

ably communicates directly with the steam-drum 6, which drum is connected with the forward water-head 3 by means of the larger water-circulating tubes 7, Fig. 2 of the drawings.

The forward or front water-head 3 is formed with the depending water-legs 8, 8', which form the forward end of the fire-box 9, the rear end of the fire-box being formed by the transverse bridge-wall 10, said wall extending to within a short distance of the tubes 11, forming the top wall of the fire-box 9. Communication is thus established between the fire-box and the combustion-chamber 12, the rear wall of which is formed by the lower portion of the rear water-head 4. Within the fire-box 9 is arranged any suitable form of grate 13. The sides of the fire-box are formed of the water-tubes 14, which tubes connect the depending water-legs 8, 8' with the rear water-head 4. The tubes 11 and 14 I shall term the "fire-box" tubes, the same being preferably somewhat larger than the boiler-tubes 2.

By means of the disclosed arrangement of the fire-box tubes a water-tube-jacketed fire-box is produced, the upper wall of which is formed by the tile-plates 15 and the side walls of tile-plates 15', which tile-plates are formed of refractory material. These tile-plates extend, preferably, to point *b* a slight distance beyond the bridge-wall 10, Fig. 2 of the drawings.

The water circulates from head 3 to head 4 through the fire-box tubes 11 and 14 and thence through the boiler-tubes 2 as heated, gradually ascending until the drum-tubes 7 are reached. These tubes convey the heated water into steam-drum 6, which, as discharged from the tubes 7, strikes against the deflecting-plate 16, secured within the steam-drum. This deflecting-plate prevents the water intermixing with the steam within the upper portion of the drum and, in fact, directs same toward the water-head 4.

The fire within the fire-box 9 is confined and prevented from coming in direct contact with the boiler-tubes 2 by means of the refractory

wall 15, which deflects the flame toward and into the combustion-chamber 12. From this combustion-chamber the hot products of combustion freely ascend and envelop the nest of 5 boiler-tubes, being confined and deflected toward the chimney by the top wall 17, supported by the drum-tubes 7.

Inasmuch as the fire-box 9 is water-tube jacketed it is obvious that the heating area 10 for the circulating water is considerably augmented and a more rapid heating of the water obtained than where the heat simply bears 15 against an upper layer of water-tubes.

The construction of the boiler is materially 20 simplified by connecting all the water-circulating tubes to a common pair of water-heads over coupling connection of the water-circulating tubes, and a freer circulation of the water procured and liability of scale-clogging 25 of the tubes materially reduced by the employment of non-sectional water-heads over sectional water-heads and couplings for the ends of the circulating-tubes.

By the described construction of a water- 25 tube boiler free and unimpeded circulation of the water is provided for.

Having thus described the invention, what

is claimed as new, and desired to be protected by Letters Patent, is—

A water-tube boiler comprising an inclosing 30 casing, a pair of non-sectional water-heads, the lower portion of which forming the front and rear wall of the combustion-chamber, circulating-tubes extending between the heads, fire-box tubes communicating with the respective heads and inclosing the fire-box, a deflector-plate arranged intermediate the fire-box and circulating-tubes adjacent said fire-box, supplemental tubes extending between the steam-drum and forward head, said tubes being 35 arranged adjacent the top wall of the casing and supporting the latter, a chimney extending upwardly from the top wall adjacent the drum, and a deflector-plate intermediate the circulating and supplemental tubes extending 40 forwardly from the rear head to a point beyond the chimney-opening.

In witness whereof I have hereunto set my hand.

THOMAS J. BARBOUR.
